INVENTOR

John Holtzman

UNITED STATES PATENT OFFICE

JOHN HOLTZMAN, OF NEW YORK, N. Y.

DOORLOCK

Application filed November 27, 1926. Serial No. 151,045.

This invention relates to locking devices with particular reference to types commonly known as dead bolts.

One of the objects of this invention is to provide a lock wherein the bolt so engages the keeper that it is impossible to pry the device open.

A further object is in the provision of means for positively retaining the bolt in a locked position whereby the device cannot be opened from the outside without employing the proper key.

These and other objects, which will become apparent as the description progresses, are accomplished by the novel construction, combination and arrangement of parts, hereinafter described and illustrated in the accompanying drawing, forming a material part of this disclosure, and in which:—

Figure 1 is a partial rear elevational, partial longitudinal sectional view of the preferred embodiment of the lock shown in a locked position.

Figure 2 is a rear elevational view of the same in an inoperative position, the cover plate being removed to show the construction.

Figure 3 is a transverse sectional view taken on line 3—3 of Figure 1.

Figure 4 is a partial longitudinal sectional view of the lock as applied to a door taken in a plane at a right angle to Figure 1.

Figure 5 is a transverse sectional view taken on line 5—5 of Figure 4.

In the drawing, the numeral 15 generally designates a rectangular casing fixed to a door 15' and having incurved lower side walls 16 in which is formed longitudinal seats 17.

Slidable on the seats is a plate 18 having a transverse slot 19, extending half-way across the plate near one end of the same, the plate being secured at 20 to a rectangular block 21 provided with a longitudinal T shaped recess 22, the block having an end plate 23 at one end, the other end being adapted to pass through an opening 24 in the casing 15 and engage a keeper 25 fixed by screws to a door frame or jamb 27.

Rotatable in the recess 22 is a cylindrical locking bolt 28 having a narrow transverse head 29 at one end and a reduced stem portion

30 at the other end passing through the plate 23 to which is fixed a small semi-circular disc 31 having a projecting lug 32 engageable in a recess 33 formed in a slide 34 one edge of which is flush against the plate 23, the slide having an elongated slot 35 engaging a headed pin 36 fixed in the plate 18 and by which it is guided.

Journalled in the front wall of the casing 15 is a tubular element 37, provided with a knob 38, the inner end of the tube being upset to engage a crank 40 in the outer end of which is fixed, a short post 41 passing through the slot 19 of the plate 18 and having a flattened surface 42 in which is secured at a right angle 60 thereto, a pin 43, engaging a recess 44 in the slide 34. The pin 43 is given movement in an arcuate path by the crank 40 and together with the disc 31 and slide 34 constitute the means for rotating the auxiliary bolt 28. It 70 will be seen that said means is arranged outside of and in spaced relation to the main and auxiliary bolts whereby the parts are easily accessible for replacement and repair.

Mounted on the top of the post 41 is a collar 45 having a semi-circular extending guide ring 46 around the outer periphery to engage a pin 47 set in a crank 48 fixed on a thimble 49 provided with a slot 50 engaging the stem 51 of the tumbler lock 52 mounted in the door 80 15' and passing therethrough to be actuated from the outside by a key 53, the thimble being rotatably secured in the offset portion 54 of a cover plate 55 fixed by screws to the casing 85 15.

Secured by a pin 57 to the collar 45 is one end of a spring 58, the other end of which is fixed at 59 to one of the curved walls 16, of the casing. Said spring serves to maintain the crank 40 in its horizontal or dead center positions and prevents undesired displacement of the parts from locked or unlocked positions.

In operation the knob 38 is revolved in a counter clockwise direction, thus, by means of the crank 40, sliding the plate 18 and the block 21 so that the block will engage the keeper 25.

When actuating the lock from the outside, the key 53 is engaged in the tumbler 52, rotat-

ing the stem 51 to cause the pin 41 to operate the slide 18, by engaging the collar 45.

Thus it may be seen that a lock has been disclosed wherein a revolving locking bolt is 5 encased in a slidable block, a combination which, when engaged in a keeper, makes the lock absolutely pry-proof and at the same time. impossible to unlock from the outside without the use of the proper key.

10 While certain preferred embodiments of this device have been shown and described, it will be understood that changes in the form, arrangements, proportions, sizes and details thereof may be made without departing from 15 the scope of the invention as defined in the appended claims.

Having thus described my invention, what I claim as new and desire to secure by Letters Patent, is:—

20 1. A lock comprising a casing, a block 25 slid- able in said casing, a bolt rotatable in said block, a slotted plate fixed to said block, a slide transversely movable on said plate and outside of said block, said slide being pro-

25 vided with a pair of recesses, a disc on said bolt, a lug integral with said disc inserted into one of the recesses, a pin in the other recess for guiding said slide, a pair of cranks journaled in said casing, and means opera-

30 tively connected to said cranks to actuate said block.

2. A lock comprising a casing, a block 35 slid- able in said casing, a bolt rotatable in said block, a slotted plate fixed to said block, said plate being slidable in said casing, a slotted transverse slide on said plate, said slide con-

35 taining a pair of recesses, a lugged disc on said bolt engageable in one of the recesses, a pair of cranks rotatable in said casing, a pin

40 on one of said cranks, a post on the other of said cranks, said post being engageable in said plate, a second pin extending from said post, said pin being engageable with said transverse slide, and means intermediate said

45 first pin and said post to actuate said block and bolt.

3. In a lock comprising a casing, a main bolt slidably mounted in said casing, a solid cylindrical auxiliary bolt, revolvably mounted 50 in an elongated recess arranged longitudinally of and extending through the side walls of said main bolt whereby the auxiliary bolt is accessible through the sides of the main bolt, and key actuated means mounted in said 55 lock casing to move the main bolt into the locked position thereof and to turn the auxiliary bolt.

4. In a door lock, a casing, a main bolt 60 slidably movable in said casing, an auxiliary bolt of substantially the thickness of the main bolt revolvably mounted in said main bolt, a crank in said casing for actuating the main bolt, a pin movable in an arcuate path by said crank, a slide directly engaged and actuated by said pin in a direction at right an-

gles to that of the movement of the main bolt and operatively connected to the auxiliary bolt for turning said auxiliary bolt and key actuated means to operate said crank.

5. In a door lock, a casing, a main bolt 70 slidably movable within said casing, an auxiliary cylindrical bolt revolvably mounted in said main bolt a revolvable member secured to the auxiliary bolt, exteriorly of and independently of the main bolt, for actuating the auxiliary bolt when said main bolt is in locked or unlocked position and a slide for operating said member, said slide being exposed in the casing for access thereto.

6. In a door lock comprising a casing, a 80 main bolt movable within said casing, an auxiliary bolt rotatably mounted within said main bolt, and mechanism for actuating said main and auxiliary bolts, said mechanism being disposed outside of said main bolt and in 85 spaced relation to the same and spring means to maintain the main bolt at dead center when said bolt is in operative position.

7. In a door lock comprising a casing, a keeper, a main bolt movable within said casing, an auxiliary bolt rotatably mounted in the main bolt and having a projection, said main and auxiliary bolts arranged to enter the keeper when said lock is in its operative position and mechanism in the casing for 95 transmitting rotatory motion to said auxiliary bolt, said mechanism including a pin, movable in an arcuate path and a transversely movable slide normally out of engagement with said pin and directly engaged by 100 said pin only when the auxiliary bolt is actuated and key actuated means to operate said mechanism.

8. A lock comprising a casing, a block 105 slid- able in said casing and of considerably less length than that of the casing, a bolt rotatable in said block, a recessed slide mounted independently of the block for movement substantially perpendicular to that of the block, said slide being exposed in the casing inwardly of and in spaced relation to the inner end of the block and being operatively connected to the bolt, and a pin mounted for arcuate movement and independent of the slide and the block, adapted to enter the recess of the 110 slide for actuating the slide.

9. In a door lock, a casing, a block having a slot therein slidable in said casing and provided with a slotted extension, a cylindrical bolt rotatable in the block and provided with 115 projections adapted to pass through the slot of said block on the rotation of the bolt, a crank rotatable in said casing, a post projecting from said crank and passing through the slot of said extension, a pin extending 120 from said post substantially parallel to said crank, and a vertically slidable element engaged by said pin and operatively connected to said cylindrical bolt.

10. In a door lock, a casing, a main bolt 130

- slidable within the casing, an auxiliary bolt rotatable in the main bolt and having a projection adapted to extend beyond said main bolt on the rotation of the auxiliary bolt, and 5 mechanism in the casing for transmitting rotary motion to said auxiliary bolt, said mechanism consisting solely of the following elements, a crank, a post projecting from said crank and arranged with the axis thereof 10 parallel to the axis of rotation of said crank, a pin extending at substantially right angles to said post, a transverse slide engaged directly by said pin when the auxiliary bolt is actuated, and a rotatable element secured to 15 the auxiliary bolt and engaging and operated by said slide.
11. In a door lock, a casing, a main bolt slidable within the casing, an auxiliary bolt rotatable in the main bolt, and mechanism 20 in the casing for turning said auxiliary bolt, said mechanism including only a crank, a post projecting from said crank, a pin extending from said post, a slide movable substantially perpendicular to the movement of the block 25 engaged directly by said pin only when the auxiliary bolt is actuated, and otherwise free of said pin, and a rotatable element fixed to the auxiliary bolt and operated by said slide; and key actuated mechanism to rotate said 30 post including a crank normally independent of said post, and a collar on said post operated by the crank on the actuation thereof by a key.
12. A lock comprising a casing, a slotted 35 plate slidable in said casing, a block fixed to said plate, a cylindrical bolt of substantially the thickness of said block mounted in said block, a crank rotatably mounted in the casing, a post carried by said crank arranged to project through the slotted portion 40 of said plate and being in permanent engagement with the sides of the slot, means for turning the bolt, a pin carried by said post for actuating the bolt turning means, 45 said crank arranged to be rotated through an arc of 180° for sliding the end of the block out of the casing and transmitting rotary motion to said bolt, a collar mounted on said post and key actuated mechanism 50 to operate said collar for rotating the post and thereby rotating the bolt and retracting said block inside the casing.
13. A door lock comprising a casing, a block 55 slidable in said casing, a cylindrical bolt rotatably mounted in said block, a plate extending from said block and having a slot, a crank journalled in said casing and in permanent engagement with said slot for moving said block, a vertically movable slide, 60 a pin on said crank directly engaging said slide for rotating said bolt, a collar mounted on said crank, and a second crank rotatably mounted in said casing engaging said collar to rotate said first crank, said 65 slot limiting the rotary motion of said first crank to an arc of 180°, whereby the block is held by said first crank against forcible retraction in the extreme locking position thereof.
14. A lock comprising a casing, a block 70 movable in said casing and adapted to be projected therefrom, a cylindrical bolt revolvably mounted in said block, mechanism to reciprocate said block and turn said bolt, said mechanism including a slotted plate, a crank rotatably mounted in the casing, a post projecting from said crank and permanently engaging said slot, whereby said slot limits the rotary movement of said crank to an arc of 180°, said crank holding the block in its outermost position against forcible retraction, a pin carried by said post for turning the bolt and a second key-controlled crank 75 to actuate the first crank.
15. A door lock comprising a casing, a block 80 slidably movable in said casing and adapted to be projected therefrom, a crank rotatably mounted in the casing, a slotted plate fixed to said block, a post projecting from said crank, and arranged to enter said slot for transmitting reciprocatory motion to said block, said post arranged to slide in the slot on the rotation of the crank, the length of said slot being such as to limit the angular movement of said crank to an arc of 85 180° in either direction, means for rotating the bolt, means on the post for engaging and operating said rotating means, and manual means to operate said crank, whereby when said crank extends horizontally in one direction, the block is projected out of the casing and holds the same against forcible retraction, and when said crank extends in the opposite direction, the block is in retracted position and is locked in said position.
16. In a door lock, the combination of a casing having a cover plate, a block slidably movable in said casing and adapted to be projected therefrom, a cylindrical bolt rotatably mounted in said block, a plate having a slot therein fixed to said block, a crank journalled in said casing and inserted into said slot, manual means for rotating said crank, said slot designed to limit the rotary movement of said crank to an arc of 180°, 90 whereby the crank reciprocates said block and holds said block against forcible retraction, a pin carried by said crank, mechanism to rotate the cylindrical bolt directly engaged and operated by said pin, a second crank revolvably mounted in the cover to operate the first crank and key actuated means to rotate said second crank.
17. In a lock comprising a casing, a block 95 slidable in said casing, a cylindrical bolt rotatable in said block, a slotted plate extending from said block, mechanism to reciprocate said block and rotate the bolt, said mechanism including a crank pivoted to the casing, a post projecting from said crank 100 125
18. In a lock comprising a casing, a block 110 slidable in said casing, a cylindrical bolt rotatable in said block, a slotted plate extending from said block, mechanism to reciprocate said block and rotate the bolt, said mechanism including a crank pivoted to the casing, a post projecting from said crank 115 130

- engaging the slotted portion of the plate, the height of said slot being such as to limit the rotary movement of said crank to an arc of 180° , and means operatively connected to the bolt and the crank for rotating the bolt, said crank when in the limiting positions thereof holding said block against movement, a second key-controlled crank to actuate the first crank and a coil spring secured at one end to the casing and at the other end to the first crank for maintaining the crank in its dead-center positions, said other end being movable with said crank from one side to the other side of the crank pivot.
18. A lock comprising a casing, a block slidable longitudinally of said casing, a plate secured to the block and having an extension projecting past the inner end of the block, a cylindrical bolt of a diameter substantially equal to the thickness of the block rotatable in the block and means in said casing between the afore-mentioned inner end of the block and the free end of said extension for rotating said bolt in the sliding of the block, including an exposed slide movable transversely of the casing and arranged exteriorly of the block on the same side of the block as is said extension, and a similarly arranged rotatable member operated by the slide.
19. A lock comprising a casing, a block slidable in said casing and having an inner end inside of the casing, and an outer end adapted to be projected through one end of the casing, a bolt rotatable in said block, a slide movable transversely of the block and arranged entirely outside of the block, and between the inner end of the block and the opposite end of the casing, means for sliding said block, a rotatable member connected to said bolt between the inner end of the block and said opposite end of the casing and operated by said slide, and manually operable rotatable means directly engaging the slide for actuating said slide.
20. A lock comprising a casing, a block slidable in said casing, a bolt rotatable in said block, a slotted plate fixed to said block, and extending therefrom, a slide movable transversely of the block and exposed on at least two sides and two ends thereof arranged on the rear surface of said plate, said slide containing a recess, and an exposed disc on said bolt and spaced inwardly from the end of the block, and having a lug for engaging the sides of said recess for rotating said bolt on the movement of the block.
21. In a lock, a casing, a rotatable bolt mounted in said casing and having a transversely arranged projection at its outer end, a keeper for said lock, said bolt being arranged to enter said keeper and interlock therewith in the operative position thereof and being retracted out of said keeper and within said casing when inoperative, and mechanism mounted in the casing for transmitting first longitudinal and then rotary motion to said bolt and vice versa, said mechanism comprising a slotted plate for the bolt movable in the casing, a crank mounted in said casing, a post carried by said crank and arranged to project through the slotted portion of said plate and adapted to be rotated through an arc of approximately 180° , said post having detachable operative engagement with the inner end of said bolt to turn the same in one direction during the movement of said crank in the slot of the plate upon the rotation of said crank in a given direction and to turn the bolt in the other direction when said crank is rotated in the opposite direction, a spring mounted in the casing to maintain said crank in alignment with said bolt for forming a dead center against forcible retraction of said bolt, and means to operate said crank.
22. In a lock, a casing, a rotatable bolt mounted in said casing and having a projection on the front end thereof, a movable slotted plate for projecting said bolt out of the casing, a crank mounted for oscillation in said casing, a post carried by said crank projecting through and permanently engaged in said slot for actuating said plate, means for detachably and operatively connecting said post to the inner end of said bolt to turn the same in one direction near the completion of the projecting movement of the bolt and in the opposite direction at the beginning of the retractive movement of the bolt inside of the casing, spring means mounted in the casing for maintaining the crank in axial alignment with the bolt in the extreme positions of the bolt, and manually operated means to rotate the crank.
23. In a lock, a casing, a revolvable bolt mounted in said casing, a longitudinally slidable member mounted in the casing for retracting and projecting said bolt into and out of the casing, a rotatable member mounted in said casing for arcuate movement and in permanent operative engagement with said slidable member, said rotatable member being in detachable operative connection with the inner end of said bolt in two positions for turning said bolt, one of said positions being when the projecting operation is about to be completed, and the other being when the bolt retracting operation is begun during one end of the arcuate movement of said member, and manually operable means to actuate said rotatable member.
24. In a lock, a casing, a cylindrical bolt rotatably supported in said casing, a slotted plate for the bolt slidably mounted in said casing, a crank revolvably mounted in one of the walls of said casing and in constant engagement with the slot of the plate for sliding said plate and said bolt, and means interposed between the crank and the inner end of

the bolt for intermittently and operatively connecting the crank with said end of the bolt for rotating the same in one direction when said bolt is projected out of the casing and rotating said bolt in the opposite direction upon its retraction, and manually operated means to operate said crank.

In testimony whereof I have signed my name to this specification.

JOHN HOLTZMAN.
